MATRIX COMPOSING AND LINE CASTING MACHINE

Paul Sckrabei, Berlin-Lubars, Germany, assignor
to Mergenthaler Linotype Company, Brooklyn,
N. Y., a company of New York

Application November 11, 1937, Serial No. 174,037
In Germany May 15, 1937

10 Claims. (Cl. 199—50)

The invention relates to matrix composing and line casting machines. In modern forms of such machines an arrangement is provided whereby one or both vise jaws can be moved towards a short line of matrices in order to quad out the line or centre it. When the quadding and centring mechanism is arranged to remain operatively connected continuously, means must be provided to render inoperative the compression of the line of matrices and allow the space-bands to become active so as to permit line justification to the limit of the stops.

The main object of the present invention is to devise a machine which will allow such action to take place and with this end in view the invention consists in a typographical composing and slug casting machine comprising means, operated by the line justification mechanism, whereby the jaws are positively separated to a prearranged extent if the line between them is not less than a prearranged length, said means being arranged to remain inoperative if the composed line is less than the prearranged length.

The invention will be clearly understood from the following description of one form (given, however, merely by way of example) which it may assume, and the description will be more readily followed by reference to the accompanying drawings, wherein:

35 Figure 1 is a view of the upper part of the vise frame fitted with the arrangement according to the invention;

Figure 2 is a separate view of the arrangement according to the invention as seen from the front;

Figure 3 is the same arrangement from the rear, that is, as seen from the interior; and

Figure 4 is a side elevation of Figure 2 or 3.

In the embodiment of the invention shown in the drawings herewith, 2 is a portion of the vise frame wherein are guided the left hand vise jaw 4 and right hand vise jaw 5. By means of links 6 and 7 the jaws are connected to two angle levers 8 and 9, which are mounted on pivots 10 in the vise frame. The two inwardly projecting arms of the levers 8 and 9 may be coupled to a vertically movable rod 13. The rod 13 after the line of matrices has been introduced between the jaws 4 and 5, performs a downward movement under the action of a spring and thereby draws the two jaws against the line of matrices.

On the angle lever 9 which is used for controlling the right-hand jaw, there is provided an abutment 26, which is adapted to contact with

an abutment 27 on one of the justification rods 28.

As shown in Figures 3 and 4, the abutment 26 is mounted on a lever 29, which is pivotally mounted on a slidable member 30. The slidable member is guided in grooves between two ledges 31 and 32 on the lever 9 and is provided with an inclined slot 33, in which engages a pin fitted to the end of a vertically guided rod 34. A link 35 connects the lower end of the said pin to the end of a crank 36, mounted on a shaft 37 which is located in two journaled members 38 and 39 fast to the lever 9, and carries at its end an adjustable knob 40. The crank is provided with a scale which co-operates with a pointer 41 fast to the machine frame. Upon the shaft 37 is also provided a locking wheel 42 adapted to co-operate with a spring controlled pin 43. The divisions of the locking wheel are such that the engagement of the pin 43 in the respective toothed notches correspond with different adjustments.

The lever 29 carrying the abutment 26 is held, by a spring 44 attached at one end to the lever and at the other end to the slidable member 30, against an abutment 45 which is itself resiliently located on the slidable member.

The mode of operation of the device is as follows:

When the justification mechanism is moved upwardly the abutment 27, fast to the top end of the justification rod, comes into contact with the abutment 26. Both abutments at their top and bottom ends converge to a point. If the abutment 26 in Figure 3 lies on the right-hand side of the abutment 27, the abutment 27, when the justifier moves upwardly, rocks the abutment 26 and the lever 29 against the action of the spring 44. The abutment 26 is thus made to yield and the upward movement of the justifier can take place without exerting any influence on the lever 9. During the downward movement, an outward swinging again takes place and the lever 29 with the abutment 26 returns into the initial position. If on the other hand the abutment 26, as indicated in Figure 3, is somewhat to the left of the abutment 27, the abutment 27, (when the upward movement of the justifier takes place), presses against the abutment 26 and the latter takes with it through the abutment 45, the slider 30 and with the latter the whole lever 9. The slider 30 in its temporary position, is prevented from moving laterally relatively to the lever 9, by the pin of the rod 34 which engages the groove 33, the rod 34 itself being secure from lateral displacement.

relatively to the lever 9, since it is vertically guided in a groove in the latter. Thus a swinging of the lever 9, about its pivotal point 10 is effected in the direction of the arrow. This 5 swinging of the lever 9 is an outward movement as Figure 3 is a view from the interior locking towards the back of the arrangement. The right-hand jaw is therefore pushed towards the right, (that is away from the line of matrices) 10 to the fixed stop at the end of the line, so as not to hinder in any way the justification of the line to its fullest possible length.

By turning the knob 40, the slideable member 30 and therewith also the lever 29 with the abutment 26 can be displaced. According to the length 15 of the full lines it is desired to set, the abutment 26 is adjusted further towards the centre of the line or towards the end. The turning of the knob causes the rod 34 to be raised or lowered, 20 and through the motion of the pin fast to the rod 34 in the inclined groove 33, the slideable member 30 is moved in a horizontal direction. If very long lines are to be dealt with, the spider 30 in Figure 2 is moved towards the extreme 25 right, and is then located in relation to the composed line at its outermost point. In these circumstances when the jaws close it is only able to pass the abutment 27 if a comparatively large space, generally more than 3 ems, has been left 30 free of matrices in the line. The spreading action of the spacebands is usually sufficient to produce line expansion up to 3 ems. If the composed line is shorter by less than the maximum of 3 ems of the adjusted full line length, 35 the abutment 26 remains on the outside of the abutment 27, and, when the justification rod moves upwardly, the abutment 27 contacts with the abutment 26 in such a manner that it forces the latter (and therewith the lever 9) away from 40 the line, and locates the jaw on the adjusted stop. If on the other hand, the free space in the line is more than 3 ems the abutment 27 rises upwardly on the left-hand side of the abutment 26 in Figure 3 and a mere outward swinging of the lever 29 carrying the abutment 26 takes place. The jaw 45 then remains in contact with the line, and a quadded line is cast in the usual manner.

In the case of short lines, the slideable member 39 is adjusted to the left by turning the knob 40 (Figure 2) for instance to the extent of 2 or 1 em 50 or less. In this case the casting of a quadded line takes place if the composed line differs to the extent of more than 2 or 1 em in excess of the adjusted size, from the length of a full line, whereas 55 so long as the lines differ to the extent of less than the adjusted size from the full line length, the jaws are withdrawn and a full line is cast.

The adjustment to 1, 2 or 3 ems is necessary in order to adapt the arrangement to different line 60 lengths. Since, according to the adjustment to 1, 2 or 3 ems, the extent to which the lever 9 can travel to the stop, is variable, the yielding capacity of the abutment pin 45 is necessary. The further movement of the lever 29, when the jaw reaches the terminal abutment, is therefore taken up by the spring of the abutment pin 45.

The inclination of the slot 33 must be such that a self-locking action takes place, and must not allow a displacement out of the adjusted position, due for example to the pressure against the slideable member.

The slideable member 30 in addition to the pertinent adjusting mechanism, may be fitted to any other convenient part of the mechanism or to the jaws themselves. A corresponding lug is

then provided on the justification mechanism, carrying an abutment adapted to come into contact with the abutment 26. The preferred constructional form however, is that illustrated in the accompanying drawings.

Having described my invention, I declare that what I claim and desire to secure by Letters Patent is:

1. A typographical composing and slug casting machine comprising jaws adapted to be moved 10 inwards to clamp a composed line of matrices and spacebands, justifying mechanism to justify the line, and means distinct from the spacebands operated by said justifying mechanism whereby the jaws are positively separated to a prearranged extent if the line between them is of not less than a prearranged length, said means being arranged to remain inoperative if the composed line is of less than said prearranged length.

2. A typographical composing and slug casting 20 machine according to claim 1 wherein said jaws are separated to the extent defining a full length line when the composed line falls short of full length by not more than a prearranged amount.

3. A typographical composing and slug casting 25 machine comprising jaws adapted to be moved inwards to clamp a composed line of matrices and spacebands, jaw operating devices, a line justification mechanism, abutments distinct from the spacebands in association with said justification 30 mechanism and with at least one of said jaws, adapted, upon initial clamping by the jaws of a line of appropriate length, to assume co-operating positions such that, upon operation of the justification mechanism, their engagement effects 35 separation of the jaws.

4. A typographical composing and slug casting machine according to claim 3 wherein said abutments have inclined surfaces upon engagement of which said jaw separation is effected.

5. A typographical composing or slug casting 40 machine according to claim 3 comprising an abutment carried by a jaw operating lever adapted, according to the position assumed by said jaw upon initial clamping of the line, to take up a position in which it is engaged by the abutment of the justifying mechanism on one or other side depending upon the length of the line clamped by the jaws.

6. A typographical composing or slug casting 50 machine comprising line clamping jaws, and operating levers, therefor, a line justification mechanism, a short lever pivoted to one of said jaw operating levers, an abutment on the free end of said short lever, and an abutment on said justification mechanism adapted, when said justification mechanism is operated, to engage on one or other side of said first-mentioned abutment according to the length of line clamped between the jaws, and thereby to separate the jaws, if the line is of not less than prearranged length, or to fail to separate the jaws, if the line is of less than said prearranged length.

7. A typographical composing and slug casting 60 machine according to claim 6 wherein means are provided such that any tendency to swing said short lever about its pivot in one direction causes movement of said jaw operating lever to separate the jaws, while said short lever can swing freely in the opposite direction about its pivot, without moving the jaw lever.

8. A typographical composing and slug casting machine comprising line clamping jaws and operating levers therefor, an abutment mounted 70

upon and laterally adjustable relatively to one of said levers, a line justifying mechanism, and an abutment thereon, adapted, upon justification of the line, to engage said abutment on said jaw operating lever if the line is of less than a pre-arranged length, and thereby to separate the jaws.

5 9. A typographical composing and slug casting machine according to claim 8 wherein said ad-

justable abutment is carried on a slide laterally movable in said jaw operating lever.

10. A typographical composing and slug casting machine according to claim 8 wherein said adjustable abutment is carried on a slide laterally movable in said jaw operating lever, said slide being adjustable by a pin engaging in an inclined slot in said slide.
